UNITED STATES PATENT OFFICE.

JOHN T. MEAD AND JOHN THOMSON, OF CLEVELAND, OHIO.

FLUE-CLEANER.

SPECIFICATION forming part of Letters Patent No. 397,509, dated February 12, 1889.

Application filed September 27, 1888. Serial No. 286,500. (No model.)

To all whom it may concern:

Be it known that we, JOHN T. MEAD and JOHN THOMSON, of Cleveland, in the county of Cuyahoga and State of Ohio, have invented 5 certain new and useful Improvements in Flue-Cleaners; and we do hereby declare the following to be a full, clear, and exact description of the invention, such as will enable others skilled in the art to which it pertains to make 10 and use the same.

Our invention relates to improvements in flue-cleaners; and it consists in certain features of construction and in combination of parts hereinafter described, and pointed out 15 in the claims.

In the accompanying drawings, Figure 1 is a plan. Figs. 2 and 3 are elevations in transverse sections on lines $x\ x$ and $y\ y$, Fig. 1. A represents a central rod having a screw- 20 threaded section, A', for attaching a handle. Near section A', and perhaps an inch or two farther forward, the rod is provided with ears a, arranged in pairs, as shown, for embracing and pivoting the respective arms B, the 25 arms and ears being pierced laterally for pintles c. At the other extreme the rod A has four laterally-projecting cruciform lugs or steady-pins, a', these lugs extending into hollow hubs B' of arms B. Springs D are lo- 30 cated inside the hub, as shown, the tension of these springs holding arms B distended as far as the engagement of end B² with rod A will admit. Arms B at the hub have lateral wings b and perpendicular wings b', all integral with the hub and with each other, and 35 beyond these the broad thin radial section B³ is of the curved variety shown, the extreme points thereof converging so nearly that they readily enter into the boiler-flue. From ap- 40 proximately the highest point of the back or outside curve of section B³ branch off spirally in either direction ribs b², the same ex- tending rearward and joining the extreme outer points of union of webs b and b'. Ribs 45 b² have sharp cutting or scraping outer edges presenting forward, and the curve of these ribs is such that they will fit a flue of given

diameter for about the entire length of the rib. These oblique or spiral sharp edges are found very effective in cleaning the boiler- 50 flue, and this flue-cleaner is operated with little force as compared with those having the scrapers approximately at right angles to the axis of the flue. Arms B and attach- 55 ments are usually of cast metal and require no fitting except drilling holes for the afore- said pintles c, and consequently when the scrapers—that is to say, the ribs b²—are worn away so as to become inoperative these arms 60 may be renewed at a trifling cost.

The sharp or scraping edges of ribs b² had better be chilled or case-hardened to increase their wearing capacity.

Of course a different set of arms are pro- 65 vided for the different sizes of boiler-flues; but the same rods A may be used for several sizes, if desired.

What we claim is—

1. In a flue-cleaner, the combination, with a central rod and arms, substantially as indicated, pivoted at their rear ends to said rod and supported upon yielding bearings near the front ends, of ribs extending spirally in opposite directions from each arm, each rib having a scraping-edge adapted to fit a flue 70 of given size, substantially as set forth.

2. In flue-cleaners, the combination, with a central rod having a series of projections on its front end, of arms pivoted at their rear ends to said rod and provided with scraping- 75 ribs extending spirally in opposite directions from each arm, and springs interposed be- 80 tween the projections on the rod and the arms for yieldingly supporting the free ends of the latter, substantially as set forth.

In testimony whereof we sign this specification, in the presence of two witnesses, this 9th day of August, 1888.

JOHN T. MEAD.
JOHN THOMSON.
